PICOT BAR ACTUATING MECHANISM

Emil J. Berger and Howard K. West, Lansdale, Pa., assignors to Dexdale Hosiery Mills, Lansdale, Pa., a corporation of Pennsylvania

Application February 12, 1948, Serial No. 7,808

13 Claims. (Cl. 66—96)

1

This invention relates to mechanism for controlling the picot bars of flat knitting machines of the "cotton" type such as are generally used in the commercial production of flat stocking blanks with ornamental saw tooth or picot edges along the fold edges of the welt tops. These welt bars are ordinarily supported by arms on fulcrum shafts from the narrowing frames of the knitting machines so that when required, they can be swung downward manually from a normally retracted raised invert position out of the way, to active position relative to the knitting needles and vice versa.

The chief aim of our present invention is to provide a simple and reliable automatic control mechanism whereby the picot bars are brought from their normal retracted positions to active position for alignment of their points with the knitting needles in readiness for the formation of the picot courses, and whereby, after the completion of the picot courses, said bars are laterally displaced relative to the needles to an angular position from which they may be subsequently swung back manually to their normal inactive out of the way positions.

Other objects and attendant advantages will appear from the following detailed description of the attached drawings, wherein Fig. 1 is a fragmentary view in front elevation of a flat knitting machine generally of the construction disclosed in U. S. Patent 1,986,577 granted to Kenneth Howie on January 1, 1935 conveniently embodying our improved picot bar control mechanism.

Fig. 2 is the organization in end elevation looking from the left of Fig. 1.

Fig. 3 is a fragmentary view corresponding to Fig. 2 with certain parts differently positioned.

Figs. 4 and 5 are fragmentary transverse sectional views taken as indicated respectively by the angled arrows IV—IV and V—V in Fig. 1.

Fig. 6 is a fragmentary view corresponding to Fig. 1 with certain parts differently positioned.

Fig. 7 is a detail view on horizontal section taken as indicated by the angled arrows VII—VII in Fig. 6.

Figs. 8, 9 and 10 are views generally like Fig. 3 in which the cooperative parts of the control mechanism are shown in still other positions; and

Fig. 11 is a fragmentary view showing other component elements of the mechanism in their normal positions.

As in the Howie patent, supra, the picot bar indicated at 1 in these drawings is connected to a horizontal fulcrum shaft 2 by supporting arms 3, and said shaft is journalled in bearings 4 and

2

4a on the fashioning frame arms 5 which are joined adjacent their swinging ends by a shaft 6 and which are secured to a rock arm 7 at the back of the machine. At their outer ends the arms 5 are connected by drop links 9 with actuating arms 10 on a rock shaft 11 journalled at a lower level in the side frames 12 of the machine and arranged to be operated, through a roller arm 13, from a rotary cam 14 on the cam shaft 15 shown in Fig. 2. Normally, the picot bar 1 is yieldingly maintained in the inverted upright retracted idle position in which it is shown in Figs. 4 and 8, through engagement of a cam projection 16a on a flexible tongue 16 (Fig. 4) with a notch 17a in a collar 17 on shaft 2. The relatively weak helical spring at 18 tends to rotate the fulcrum shaft 2 counterclockwise in Fig. 2, and a slot and also to shift said shaft leftward in Fig. 1 for interlock of a shouldered clutch collar 20 thereon with a correspondingly shouldered mating boss 21 on the bearing 4 to maintain the picot bar 1 in its lowered or active position and the points 1a thereof in operative alignment with corresponding needles in the usual needle bar 22. The narrowing point combs at 25, 26 are mounted on slide bars 27, 28 and normally occupy the positions shown in Fig. 1, outwardly beyond opposite ends of the needle bar 22. The narrowing combs 25, 26 are arranged to be shifted back and forth horizontally by a screw spindle 29 which is threadedly engaged by follower nuts 30, 31 connected to the slide bars 27—28 and actuated through a pair of intermeshing gears at 32 and 33. As in the Howie patent, this racking mechanism includes control means whereby the shift of the narrowing combs 25, 26 is limited during formation of the picot courses, to a distance equal to the single spacing of the needles, the shoulders on the clutch collar 20 and the mating boss 21 of bearing 4 being of a width to allow this action without disengagement. This limited back and forth shift is imparted to the picot bar 1 by cooperation of a finger 35 extension on the follower nut 30 with an adjustable stud 36 in an arm 37 secured to the rock shaft 2 in a manner similar to that disclosed in the Howie patent. When the picot bar 1 is swung upward to its normal retracted idle position as in Figs. 4 and 8, the arm 37 is moved out of the path of the finger extension 35 on the nut 30 so that the narrowing combs 25 and 26 may be moved inward to operative positions in relation to the needles and be progressively shifted as required during the fashioning phases of the knitting in the well known way.

In adapting our invention to a knitting machine characterized as above briefly described, we extend the fulcrum shaft 2 somewhat beyond the bearing 4 and there apply to it a normally lax torsion spring 40 which, in practice, is somewhat heavier and hence stronger than the spring 18, and which, when energized, tends to rotate the shaft 2 clockwise in Fig. 2. One end of the spring 40 is secured to a collar 41 fixed on shaft 2 and the other to a roller arm 42 which is rotatively free on said shaft, and which is arranged to be acted upon by an edge cam 43 secured to the corresponding end of an auxiliary shaft 45. As shown, the auxiliary shaft 45 extends parallel to the rock shaft 2 and is rotatively supported at opposite ends in the bracket 4 of the narrowing frame, and in a bracket 46 which conjointly with another generally similar bracket 47, supports the guard 48 for the picot bar. Rotative movement is imparted to the shaft 45 as later on explained through a pair of intermeshing spur gears 53 and 54 whereof the larger one carries a crank pin 52 which, through a pitman 53 (see Fig. 2), is connected to an arm 55 pivoted at 56 on a fixed bracket 57 at the back of the machine. The arm 55 is subject to the pull of a tension spring 58 and has a lateral tooth projection 55a to cooperate with a sectoral cam 59 fast on a shaft 60 which is rotatively supported in one of the end frames 42 of the machine. Also secured to the shaft 60 is a ratchet wheel 61 which is arranged to be picked by a pawl 62 on one extremity 63a of a bell crank 63, fulcrumed at 64. The other extremity 63b of the bell crank 63 carries a roller 65 that rides on the periphery of another rotary cam 66 on cam shaft 15. A spring 67 acts upon the extremity 63a of the bell crank 63 to maintain the roller 65 yeldingly engaged with the rotary cam 66. The activity of the pawl 62 is governed by a shield 68 which is free on the shaft 60, and which is adapted to be operated through a Bowden wire 69 from the usual timing chain (not illustrated) of the machine. The cam 43 normally occupies the position in which it is shown in Fig. 8 determined by engagement of a finger 70 on the shaft 45 with the shaft 6. To the fulcrum shaft 2 somewhat inward of the arm 37 is secured a radial projection in the form of a small arm 71 (Fig. 1) with a roller arranged to be acted upon by a trip finger 72 set screwed to the shaft 45. In order to damp the fall of the picot bar 1 when automatically released to the action of gravity as hereinafter set forth, we have provided a dash pot whereof the cylinder 75 is mounted on the bracket 46 as in Fig. 1, and whereof the piston 76 at its outer end has a pivotal connection at 77 (see Fig. 5) with the strap 78 of an eccentric 79 on the fulcrum shaft 2. As shown, the dash pot piston 76 has an axial duct 80 which terminates in a lateral bleed port at 81.

Operation

Assuming that the picot bar 1 is in the normal raised retracted position of Fig. 4 with the parts of the control mechanism in the normal positions in which they are shown in Figs. 8 and 11, and that half the length of a stocking welt has been knitted in the machine to the point where the picot courses are to be formed, the shield 68 (Fig. 2) is actuated under control of the measuring chain to release the pawl 62 for picking of the ratchet wheel 61. At the first pick of the ratchet, the shoulder 59a of cam 59 (Fig. 11) acts upon the arm 55 and moves it counterclockwise, with attendant impartation of a partial clockwise ro-

tation to the gear wheel 51. Due to the ratio of the gear wheels 50 and 51, this movement is multiplied in its transmission to the shaft 45 with the result that the cam 43 and the fingers 70 and 72 thereon are turned counter-clockwise to the position of Fig. 9. During this movement, the trip finger 72, in acting upon the small arm 71, turns the shaft 2 clockwise slightly and, upon passing dead center as in Fig. 9, the picot bar 1 will fall forwardly of its own weight, the fall being damped by action of the dash pot 75. Also during this movement the arm 42 is swung upward so that its roller engages cam 43 within the bight 43a thereof and intercepts the picot bar 1 as shown in broken lines in Fig. 9.

On the next pick of ratchet wheel 61 (Fig. 2) the cam 59 is rotatively shifted further in the same direction so that the rise 59b thereof is moved into engagement with the tooth projection 55a of lever 55, whereby, through the pitman 53, the gear wheel 51 is further turned clockwise to the position of Fig. 10. During additional counterclockwise rotary movement thus transmitted to the auxiliary shaft 45, the lobe 43c of cam 43 acts upon the roller arm 42 with resultant energization of the torsion spring 40 which overcomes the weaker spring 18 and thereupon acts upon the picot bar 1 to swing it inward from the broken line intermediate angular position to the final active full line position in Fig. 10 relative to the needles whereupon the clutch collar 20 on shaft 2 will automatically interlock with the boss 21 of bearing 4 as in Fig. 1. At the same time, the stud 39 on arm 37 will be moved into position in front of the finger extension 35 of the follower nut 30. With the picot bar 1 now down in its active position, the narrowing frame is dipped for lowering of the picot points 1a to take the loops from corresponding needles, then raised to lift the points clear of the needles, then shifted rightward in Fig. 1 to the extent of one needle through a rotative shift imparted to the screw spindle 29 in one direction, then again lowered so that the loops are deposited on immediately adjacent needles, and then raised again, whereupon the picot bar is shifted leftward back to its original position by a reverse rotary shift of the screw spindle—all this being effected in the same way as described by Howie.

After the picot courses have been formed, the ratchet 61 is picked another tooth whereby the high spot 59b of cam 59 will pass beyond the tooth 55a of arm 55 which will be swung back by the spring 58 until said tooth bears upon the concentric edge portion 59c of said cam as in Fig. 2. As a result, the gear 51 will be turned counterclockwise and the cam 43 clockwise to the position shown in Fig. 2 when the lobe 43b of said cam will act upon the roller arm 42 to move the latter counterclockwise with attendant de-energization of the spring 40. Somewhat later in the stocking knitting cycle as the screw 29 is operated to give the follower nuts 30 and 31 their first two-needle inward shift in preparation for narrowing, the fulcrum shaft 2 is moved rightward by action of the finger 35 on said nut with the arm 37 on said shaft to an extent sufficient for the release of the clutch collar 20 from locking engagement with the boss 21 of the bearing 4. Upon this disengagement, the weaker spring 18 immediately exerts its torsional influence upon the fulcrum shaft 2 to swing the picot bar 1 outward; i. e., back to the broken line angular position in Fig. 9. In the meantime, as a consequence, the ratchet wheel 61 is given

a few more picks, the cam 59 is further turned clockwise until its edge 59c passes beyond the tooth 55a of arm 55 when the latter is pulled rightward from the position of Fig. 2 and the gear 51 moved counterclockwise until it re-assumes the position of Fig. 3 with the shaft 45 stopped by re-engagement of the finger 78 with the hub of said gear. The picot bar 1 may thereupon be swung up by hand to its normal raised retracted rest position in Figs. 4 and 8.

Having thus described our invention, we claim:

1. In a straight knitting machine having a series of needles, a narrowing frame, a picot bar with supporting arms secured to a horizontal fulcrum shaft rotatively borne by the narrowing frame, and means for releasably maintaining the picot bar in an inverted raised retracted upright position; picot bar control mechanism including means automatically operative to trip the picot bar for gravity fall, spring means for momentarily intercepting the picot bar in a downward angular inoperative position beyond the needles, and means automatically operative in opposition to the spring means to thereupon swing the picot bar from said angular position to operative position in relation to the needles.

2. The invention defined in claim 1, wherein the machine is provided with a second spring means tending to swing the bar toward its operative position, and further including means automatically operative after the picot bar has functioned to release it to the action of the first spring means whereby it is swung back to the angular position in readiness for manual restoration to its normal retracted position.

3. The invention defined in claim 1, further including means for damping the fall of picot bar.

4. The invention defined in claim 1, in which the machine has a main cam shaft, and further including interposed connections whereby the several component means of the control mechanism are actuated from the main cam shaft.

5. In a straight knitting machine having a series of needles, a narrowing frame, a picot bar with supporting arms secured to a horizontal fulcrum shaft rotatively borne by the narrowing frame, and means for releasably maintaining the picot bar in an inverted raised retracted upright position; picot bar control mechanism including a normally lax torsion spring associated with the fulcrum shaft, means automatically operative when use of the picot bar is desired to first trip it so that it may fall of its own weight and to intercept it in an intermediate angular position, and means automatically operative thereafter to energize the torsion spring for action upon the fulcrum shaft to bring the picot bar into final operative relation to the needles.

6. The invention defined in claim 5, in which the machine is provided with spring means tending to swing the picot bar to its inactive position, and further including means automatically operative after the picot bar has functioned to relax the torsion spring and release the bar to the action of the spring means whereby it is swung back to the angular position in readiness for manual restoration to its normal retracted position.

7. The invention according to claim 5, further including means for damping the fall of the picot bar.

8. The invention according to claim 5, in which the machine has a main cam shaft, and further including interposed connections whereby the several component means of the control mechanism are actuated from the main cam shaft.

9. In a straight knitting machine having a series of needles, a narrowing frame, a picot bar with supporting arms secured to a horizontal fulcrum shaft rotatively borne by the narrowing frame, and means for releasably maintaining the picot bar normally in an inverted retracted upright position; picot bar control mechanism including an auxiliary shaft on the narrowing frame in parallel relation to the fulcrum shaft, a rotary cam affixed to the auxiliary shaft, a finger on the auxiliary shaft normally in engagement with a radial projection on the fulcrum shaft, a roller arm free on the fulcrum shaft and normally out of the range of the cam, a normally lax torsion spring with one end thereof connected to the fulcrum shaft and the other to the roller arm, and means automatically operative when use of the picot bar is required to impart a partial turn to the auxiliary shaft at the initiation of which the fulcrum shaft is turned slightly by action of the finger upon the radial projection and the picot bar thereby released to fall by its own weight until arrested in an intermediate angular position upon contact of the roller arm with the cam, and as the rotative movement of the auxiliary shaft continues to completion, the torsion spring is energized by action of the cam upon the roller arm, and the fulcrum shaft further turned to finally bring the picot bar into operative relation to the needles.

10. The invention according to claim 9, in which the machine is provided with spring means tending to swing the picot bar toward its normal retracted position, and further including means automatically operative after the picot bar has functioned, to release it to the action of the spring means whereby it is swung back to the angular position in readiness for manual restoration to its normal retracted position.

11. The invention according to claim 9, further including a dash pot for damping the fall of the picot bar, the cylinder of the dash pot being connected to the narrowing frame and the piston rod thereof pivotally connected to the strap of an eccentric on the fulcrum shaft.

12. The invention according to claim 9, in which the machine has a main cam shaft, and further including interposed connections whereby the several component means of the control mechanism are actuated from the main cam shaft.

13. The invention according to claim 9, further including means for damping the fall of the picot bar.
